UNITED STATES PATENT OFFICE.

LOUIS GOHLKE, OF GRAND RAPIDS, MICHIGAN.

DESIGN FOR A CARPET-SWEEPER STAND.

SPECIFICATION forming part of Design No. 23,976, dated January 29, 1895.

Application filed September 14, 1894. Serial No. 523,044. Term of patent 7 years.

To all whom it may concern:

Be it known that I, LOUIS GOHLKE, a citizen of the United States, residing at Grand Rapids, in the county of Kent and State of Michigan, have invented a certain new and original Design for Carpet-Sweeper Stands, of which the following is a specification.

This design relates to a carpet sweeper display stand and the distinctive features thereof consists of a central, oval shield, in the midst of a group of involute scroll ornaments, and about which the carpet sweepers are grouped on suitable supports attached to said scrolls, and supporting scroll ornamented legs forming a base to the structure, as more fully illustrated in the accompanying drawing, in which—

A represents a convex oval shield having a beaded border, and a curved diagonal bar A' dividing it into two substantially equal fields. Said shield is surmounted by two oppositely

turned involute scrolls B, B. Beneath said shield and supporting the same are two other somewhat smaller, oppositely turned involute scrolls C, C, and at each side of said shield two other pairs of still smaller scrolls D, D, of like character. Centrally above the upper scrolls B, B, and upwardly projecting is a stud F and at each side of said shield and projecting from the scrolls D, D, are two other similar studs F, F.

Having thus described my invention, what I claim is—

The design for a carpet sweeper display stand, substantially as herein shown and described.

In testimony whereof I affix my signature in presence of two witnesses.

LOUIS GOHLKE.
